DISPLAY STAND

Glenn A. Bishop, Wilmette, Robert B. Bishop,
Arlington Heights, and Charles E. Jones, Chicago, Ill.

Application January 15, 1948, Serial No. 143,814

Term of patent 14 years

(Cl. D80—9)

To all whom it may concern:

Be it known that we, Glenn A. Bishop, a citizen of the United States, residing at Wilmette, in the county of Cook and State of Illinois, Robert B. Bishop, a citizen of the United States, residing at Arlington Heights, in the county of Cook and State of Illinois, and Charles E. Jones, a citizen of the United States, residing at Chicago, in the county of Cook and State of Illinois, have invented a new, original, and ornamental Design for a Display Stand, of which the following is a specification, reference being had to the accompanying drawings forming a part thereof, in which:

Fig. 2 is a transverse sectional detail, with parts removed, taken through the upper portion of the stand and enlarged with respect to Fig. 1;

Fig. 3 is a fragmentary top view of the stand enlarged with respect to Fig. 1; and

Fig. 4 is a fragmentary side view of the stand uprights enlarged with respect to Fig. 1.

The opposite sides of the stand are alike and substantially symmetric.

We claim:

The ornamental design for a display stand, substantially as shown and described.

GLENN A. BISHOP.
ROBERT B. BISHOP.
CHARLES E. JONES.
